(57) **CLAIM**

The ornamental design for a folding chair as shown and described.

DESCRIPTION

FIG. 1 is a front, left and top perspective view of a folding chair, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of detail 9 in FIG. 1.

The dot-dash broken lines depict the sewing thread parts of the folding chair that form no part of the claimed design. The short dashed broken lines in FIGS. 1-8 show portions of the article that form no part of the claimed design.

The longer dashed broken lines in FIGS. 1 and 9 depict the boundaries of the enlargements that form no part of the claimed design.
